REMOVABLE SASH LOCK ASSEMBLY

Joseph W. Price, Topton, Pa., assignor to Transportation Sash Company, Inc., Topton, Pa., a corporation of Pennsylvania

Application October 30, 1950, Serial No. 192,883

7 Claims. (Cl. 189—72)

1

The present invention relates to metal window sashes for transportation vehicles and more particularly to latches for said sashes.

The conventional sash latch is installed in the window sash in such manner that access to the latch elements for adjustment or repair may be had only by removing the sash from its casing.

A primary object of my invention is to provide a latch assembly affording access to the latch mechanism and actual removal of the mechanism while the sash remains in the window casing.

A further object is to provide a latch mechanism which is substantially rattle proof under vibration.

Another object is to provide a latch mechanism of simple construction affording easy assembly of the latch in and disassembly from the window sash.

The invention resides also in certain novel and advantageous structural features hereinafter specifically described, and illustrated in the attached drawings wherein:

Fig. 1 is a fragmentary perspective view of the lower right hand corner of a window sash equipped with a sash lock according to my invention, said view illustrating the interior elements of the sash lock in partially withdrawn state;

Fig. 2 is a perspective view of the cover plate and latch release mechanism removed from the window sash;

Fig. 3 is an elevational view of the sash lock in operative position in the window sash;

Fig. 4 is a sectional view taken along the line 4—4 of Fig. 3;

Fig. 5 is an elevational view with a fragment of the sash broken away to show the internal mechanism of the lock in operative position;

Fig. 6 is a sectional view along the line 6—6 of Fig. 5; and,

Fig. 7 is a perspective view of a modified form of cover plate and latch-release mechanism embodying the principles of the present invention.

Referring to Figs. 1 and 2, reference numeral 10 represents a window sash the lower horizontal member 11 of which is hollow and thereby adapted to house an internal latch assembly designated generally by the reference numeral 13. Specifically, the assembly consists of a latch element 14, a member 15 in which the latch 14 is slidably supported, a cover plate 16 which is detachably secured to the member 15 and a latch-actuating lever 17 which is mounted in the cover plate and by means of which the latch may be retracted against pressure of a spring 18 attached

2

to the latch and reactive with the support 15 to urge the latch toward an advanced position wherein the end 19 of the latch projects beyond the side edge 20 of the sash as illustrated.

5 The member 15 consists of a base or body element 21 having an upstanding arm at each end, numbered 22 and 23 respectively, and an intermediate arm 24. Each of the arms has a recess, 25, 26 and 27 respectively, in the face thereof, in which the latch 14 is mounted as hereinafter described. The base 21 of the member 15 seats upon the bottom wall 28 of the hollow sash member 11, and is secured to the said wall by screws 29 passing upwardly from the underside 10 of the wall as shown in Fig. 5. The arm 23 and the proximate end of the base 21 abuts the inner side of the side member 30 of the sash and is secured to this member by screws 31 which are passed through the member 30 from the outer edge thereof. The member 15 thus serves to reinforce and strengthen the joint between the sash members 11 and 30. As shown, the member 30 is slotted at 32 in alignment with the latch-receiving recesses 25, 26 and 27 of the member 15 for passage of the end 19 of the latch.

15 The latch 14 comprises a major longitudinal portion 39 of rectangular cross section which terminates in the end 19, said end being shaped for cooperative engagement with suitable notches or the like in the confronting face of the window frame (not shown) to support the sash in elevated position in the frame to which it may be adjusted. Near the left hand or inner end of the rectangular portion 39 and in the under side thereof is a recess 41 the purpose of which will be hereinafter described. Fixed to the inner end of the portion 39 and extending longitudinally therefrom, is a rod 42 having a laterally expanded end 43. Slidably mounted on rod 42 is a U-shaped stirrup 44 which embraces the end of the part 39, the legs of the stirrup being sufficiently long to overlap the near side of recess 41 in part 39. A spring 45 is confined between stirrup 44 and a washer 46 at the outer end 43 of the rod 42, displacement of the washer from the rod being prevented by the expanded formation of the latter.

20 In assembly the portion 39 of the latch is slidably supported on angular projections 47 in the bottoms of the recesses 26 and 27 in the support arms 23 and 24 with the end 19 of the latch projecting through slot 32 in sash member 30. The rear end of the rod 42 occupies the recess 25 in arm 22, the washer 46 seating against the inner face of said arm, and the spring exerting pres-

sure against the stirrup 44 and through the stirrup on the proximate end of the part 39 of the latch to project the latter through the slot 32. The movement of the latch under pressure of the spring is limited by the lever 17 which engages the recess 41 as described below.

Access to the support member 15 for insertion and removal of the latch in and from the sash is afforded by an opening 48 in the inner side of the sash, said opening being generally rectangular in shape with circular recesses 51 and 52 in the upper edge thereof near the respective ends. The opening 48 is normally closed by the detachable cover plate 16 as described below.

The cover plate 16 is of generally rectangular shape and has inward bosses 54 and 55 arranged to fit snugly in the recesses 51 and 52 of the opening 48 so as to position the cover plate accurately with respect to the opening and to the support member 15. The bosses 54 and 55 register with tapped holes 56 and 57 in the upper ends of arms 22 and 24, and apertures 58 and 59 extend through the bosses to the forward face of the plate for reception of screws 61 and 62 which, entering the tapped holes 56 and 57, secure the plate in place over the opening 48 and against the inner face of the sash.

An aperture 63, best shown in Fig. 4, is provided in the cover plate 16 for reception of a cylindrical boss 64 on the lever 17, said boss neatly fitting the said aperture and forming a journal for the lever in the plate. The boss has a rectangular projection or key 65 which neatly fits a correspondingly shaped opening 66 in the flat body portion 67 of a member 68 which when secured to the inner end of the boss by means of a screw 69 and lock washer 71 functions in part as a washer to secure the lever 17 rotatably in the cover plate. The member 68 has a narrow tongue 72 which projects inwardly for engagement in the recess 41, it being noted that when the tongue occupies the recess it is confined laterally between the edge of the stirrup 44, under pressure of the spring 45, and the opposite side of the recess, as shown in Fig. 5.

The normal projected position of the latch, shown in Fig. 3, is determined by a lug 73 on the inner face of the cover plate which lies in the path of the tongue 72 and acts as a stop to limit the rotary movement of the lever 17. Thus, with the latch normally extended, the lever will assume the position shown in Fig. 3 wherein the tongue 72 is pressed by action of spring 48, against the lug 73. Clockwise movement of the lever from this position (as viewed in Fig. 3) will cause the tongue to move away from the lug and to retract the latch so that the end 19 is withdrawn into the sash. It will be noted that the cover plate 16 has a lug 74 which is arranged to register with the recess 25 and which when the cover is in place projects into and effectively closes the mouth of the recess so as to preclude displacement of the end of the rod 42 from the recess. As will be apparent the other end of the latch is guided in the slot 32 so that displacement of the latch from recesses 26 and 27 is precluded.

An important feature of the device described above is the high degree of accessibility which it affords for repair or adjustment of the latch elements. After removal of the cover plate by release of the two retaining screws 61 and 62, the latch may be readily removed from the support by first withdrawing the end of the rod 42 from the recess 25 and outwardly through the opening 48 to an extent permitting the longitudinal move-

ment of the latch required to withdraw the outer end from the slot 32. When the latch is thus removed the spring 48 will be retained on the rod 42 by engagement of the washer 46 with the expanded terminal end of the rod. The latch may be readily inserted by a reversal of the removal operations.

It will be noted that in the aforescribed embodiment, the lever 17 is designed to function both as a latch release device and also as a finger grip in supporting and manipulating the sash. To this latter end the lever is provided with the outwardly projecting flange 75 along its upper edge to serve as an abutment for the fingers. In the embodiment illustrated in Fig. 7 the finger grip for manipulating the sash is divorced from the latch-retracting lever. Thus, the cover plate 76 is provided with an outwardly extending flange 77 which affords a finger grip; and the latch lever 78, which in this case is pocketed in an outwardly bowed portion 79 of the cover plate, has a transverse arm 81 at the top which overlies the flange 77 and is normally elevated above the flange as illustrated. By placing the fingers under the flange and the thumb on top of the arm 81 and by then exerting a force sufficient to depress the arm toward the top of the flange, the latch may be released and the sash raised or lowered in well known manner. In all other essential respects the embodiment corresponds to the one previously described.

I claim:

1. In a sliding metal window sash, a transverse hollow bottom member having an elongated opening in the face thereof, an upright side member joining one end of said bottom member and having a channel extending inwardly from the outer edge thereof to the interior of the bottom member, a latch supporting element located in the interior of the bottom member at the junction of that member with the side member and having latch receiving recesses opening to the side of the element which confronts the said opening in the bottom member, means for rigidly securing said element in place within said bottom member, a latch element slidably and detachably mounted in said recesses with one end thereof extending freely through said channel, a spring normally resiliently retaining the latch element in extended position projecting beyond the said outer edge of the side member, the said elongated opening being dimensioned and arranged to permit insertion and removal of said latch element from said recesses, a detachable cover plate for said opening, and a latch retracting device carried by, and including an actuating element on, the outer face of said cover plate.

2. A window sash according to claim 1 wherein in the cover plate comprises means obstructing and effectively closing the mouth of one of said recesses.

3. In a metal window sash a transverse hollow bottom member having an elongated opening in the face thereof, an upright side member joining one end of said bottom member and having a channel extending inwardly from the outer edge thereof to the interior of said bottom member, a latch element slidably and detachably mounted in said hollow bottom member with one end thereof extending freely through said channel for advance and retractive movements therein, a latch supporting element of relatively heavy metal in comparison to the other structural elements of the sash located in the interior of the bottom

member at the junction of that member with the side member and having means for supporting and guiding said latch member for said advance and retractive movements, said element comprising an elongated base portion adapted to seat within said hollow bottom member flush against the bottom wall thereof, said base portion having an upstanding arm at each end thereof, the said forward arm arranged flush against said upright side member, screw means penetrating said bottom wall of the bottom member into threaded engagement with said base portion, other screw means penetrating said upright side member into threaded engagement with the said forward upstanding arm so as to afford extended rigid surface contact between said sash members and said support for transmission to the former of thrusts imposed through the latch member upon the sash, said latch-supporting and -guiding means comprising recesses in said upstanding arms opening to the side of the element which confronts the said elongated opening in the face of the bottom member, the said elongated opening being dimensioned and arranged to permit insertion and removal of said latch element in and from said recess, a detachable cover plate for said opening, and a latch-operating device carried by and including an actuating element on the outer face of said cover plate.

4. A sash according to claim 3 wherein said base portion is provided with a third recessed upstanding arm intermediate said forward and rear arms and comprises tapped holes at the junctions of said intermediate and rear upstanding arms with said base member for the reception of said base-securing screw means and wherein further the free ends of said intermediate and rear arms are provided with tapped holes for releasably securing said cover plate to the support element.

5. In a metal window sash a transverse hollow bottom member having an elongated opening in the face thereof, an upright side member joining one end of said bottom member and having a channel extending inwardly from the outer edge thereof to the interior of said bottom member, a latch-supporting element of heavy metal in comparison to the other structural elements of the sash located in the interior of the bottom

member juncture of that member with the side member, and having receiving recesses opening to the side of the element which confronts the said opening in the bottom member, said element comprising an elongated base portion adapted to seat within the channel of said bottom member and having an upstanding arm at the forward and rearward ends thereof, each said arm containing one of said latch-receiving recesses, means for rigidly securing said element in place within said bottom member, a latch element slidably and detachably mounted in said recesses with one end thereof extending freely through said channel, a spring seating against the rearward upstanding arm normally resiliently retaining the latch element in extended position projecting beyond the said outer edge of the side member, the said elongated opening being dimensioned and arranged to permit insertion and removal of said latch element from said recesses, a detachable cover plate for said opening, and a latch-operating device carried by and including an actuating element on the outer face of said cover plate.

5. A sash according to claim 5 wherein the forward upstanding arm abuts the interior side of said upright side member, and wherein further means is provided for rigidly securing said side member to said forward arm.

7. A sash according to claim 5 wherein said latch-supporting element includes a third upstanding arm intermediate said forward and rearward arms, said third upstanding arm containing one of said latch-receiving recesses, and wherein the said cover plate is detachably secured to said rearward and said third upstanding arms.
